DEVICE FOR SEVERING METALS.

932,739.

Specification of Letters Patent. Patented Aug. 31, 1909.

Application filed January 5, 1907. Serial No. 350,990.

To all whom it may concern:

Be it known that I, ERNST WISS, a subject of the German Emperor, and residing at Griesheim-on-the-Main, Germany, have invented certain new and useful Improvements in Devices for Severing Metals, of which the following is a specification.

This invention relates to devices for severing metals by supplying a combustible gas mixture rich in oxygen, and pure oxygen in the form of a fine jet at a suitable pressure, to the part where the cutting is to be effected, the metal being oxidized and the oxide dispersed.

15 In the devices of this kind hitherto known for carrying out this operation, a heating flame and a jet of oxygen at high pressure have been supplied to the part to be severed. This flame and this jet have not been coincident in their action as regards either space, or time, for the flame of combustible gas and oxygen was first supplied to the required place, and a jet of oxygen was supplied after shifting the said jet of gas and oxygen. This separation of the two operations as regards time and space is based on the erroneous impression that the heating flame plays a part, during the severing operation, which it does not play, for the time 20 of heating, especially in the case of thick pieces of metal, is not sufficient, to pre-heat the piece of metal, to the temperature of combustion despite the comparatively high speed of severance. In the process, the 25 combustion, which progresses at a uniform rate, effects first the required pre-heating of the metal at the cutting place, the heating flame starting the severance *i. e.* sufficiently pre-heating the starting point while, when the place of severance has been cooled by the jet of oxygen the operation has to be started again. In such a device it is therefore quite possible to cool the place of severance by the blast of oxygen.

45 The present invention has for its object to obviate this disadvantage by causing the supply of the heating flame and the oxygen jet to coincide both as regards time and place. The heating flame need not keep the 50 full thickness of the metal to the temperature of combustion, but only the sharply undercut front edge of the place of severance and the cooling of the place of sever-

ance by the jet of oxygen and the interruption of the cut are thus avoided.

55 In order to sufficiently heat, by means of a single apparatus, any thickness of metal, it is necessary to vary the quantity of heating gas mixture and to adapt the width of the nozzle to the quantity of gas mixture 60 then used.

This invention provides a device by means of which this object is attained in a simple manner by making the oxygen nozzle capable of movement to effect the adjustment, 65 according to requirements, of the annular opening through which the gases for the heating flame issue.

In the accompanying drawing, Figure 1 is 70 a vertical section of the device in accordance with this invention, and Fig. 2 a horizontal section on the line *a—b* of Fig. 2.

In external appearance the device 75 resembles a Daniel burner, but differs therefrom in that the inner supply tube is slidably arranged in relation to the outer tube and that both the inner surface of the outer supply tube and the outer surface of the inner tube are conical, but have not the same taper, the outer tube consisting 80 essentially of a two-part casing, the body portion 2 and the detachable nozzle 6, which is socketed and screw-threaded to receive a screw-threaded projection of the casing. The inner tube 3 projects through a stuffing 85 box at one end of the casing and terminates in a detachable nozzle 4, and the outer casing or tube is contracted internally at the open end and the inner tube is also tapered at the outer end so that there is an intervening annular space, the inner tube being maintained 90 concentric with the outer tube by means of external wings or lugs 5. Through a tube 1 a mixture of combustible gas and oxygen is supplied to the outer burner tube 2 while 95 another tube 3 supplies oxygen at a regulated pressure.

Before using the device, the tube 3 is shifted inside the tube 2, and nozzle 6 to such an extent that the nozzle 4, projects beyond the outer nozzle 6, thereby insuring that the jet of oxygen issues as near as possible to the metal to be operated on while the annular opening for the supply of combustible gas and oxygen is more, or less, throttled. In 100 this way the efflux velocity of the mixture

of gases for the flame is so regulated that it is greater than the then prevailing speed of ignition and back firing is prevented.

By means of the arrangement in accordance with this invention it is possible to cut metal of any thickness, the width of cut being about two millimeters while no interruption of the work will take place.

It will be noted that the tube to which the oxygen is supplied is the internal tube and that it projects beyond the external tube or casing. This is a matter of great importance, maintaining the oxygen jet in its original shape at as great a distance as possible from the nozzle through which the burning mixture escapes, as this results in a clean cutting or severing of the metal which cannot be attained if the oxygen is brought into intimate contact with the burning mixture before the latter issues from the outer tube or casing. In other words I have found that by maintaining a jet of oxygen beyond the point where the combustible mixture is ignited I am able to secure a jet which results in a much sharper cutting effect than is possible to secure if the oxygen and the burning mixture are combined before the oxygen is brought to the form of a projecting jet.

In order that the heating flame shall always meet as sharp an edge as possible and pre-heat the metal sufficiently, it is advisable that the flame be blown against the edge at an obtuse angle to the material rather than at a right angle thereto.

Having now particularly described and ascertained the nature of my said invention and in what manner the same is to be performed I declare that what I claim is—

1. The combination in a burner for sever-

ing metals, of a tube or casing open and internally tapered at one end, and means for supplying a mixture of combustible gas and oxygen thereto, and a tube within said casing externally tapered at one end and projecting at said end beyond the contracted end of the casing, and means for supplying said tube with oxygen, for the purpose set forth.

2. The combination in a burner for severing metals, of a tube or casing open and internally tapered at one end and means for supplying a mixture of combustible gas and oxygen thereto, and a tube within said casing externally tapered at one end and projecting at said end beyond the contracted end of the casing, and means for supplying said tube with oxygen, said tube and casing relatively adjustable to vary the dimensions of the discharge opening around the inner tube, for the purpose set forth.

3. The combination in a burner for severing metals, of a casing provided with a detachable nozzle contracted internally at the open end and means for connecting said casing with a supply of combustible gas and oxygen, and a tube within said casing provided with a detachable nozzle tapering externally and projecting beyond the end of the casing and longitudinally adjustable in respect to the casing and communicating with means for supplying oxygen thereto.

In testimony whereof I have signed my name to this specification in the presence of two subscribing witnesses.

ERNST WISS.
